(57) **CLAIM**

The ornamental design for a door for washing machine, as shown and described.

DESCRIPTION

1. Door for washing machine

1.1 is a perspective view of a door for washing machine, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof; and

1.7 is a bottom plan view thereof.

The broken line showing in figures 1.3-1.7 is for the purpose of illustrating portions of the door for washing machine that forms no part of the claimed design.
